DESIGN FOR A SET OF GAME PIECES

Alma M. Lassen, New York, N. Y.

Application February 28, 1936, Serial No. 61,404

Term of patent 7 years

To all whom it may concern:

Be it known that I, Alma M. Lassen, a citizen of the United States, residing at New York city, in the county and State of New York, have invented a new, original, and ornamental Design for a Set of Game Pieces, of which the following is a specification, reference being had to the accompanying drawing, forming part thereof.

The figure is an elevation, and illustrates my new design as comprising forty-eight elongated

and relatively thin flat strips, the strips each having a design symbolic of the game, each having a number, and each having an opening adjacent the lower end. The backs of the respective strips are blank.

I claim:

The ornamental design for a set of game pieces substantially as shown and described.

ALMA M. LASSEN.
